UNITED STATES PATENT OFFICE.

EGBERT S. CADY, OF CEDARVILLE, MICHIGAN.

IMPLEMENT DESIGNED FOR MARKING CIRCLES.

1,115,390.

Specification of Letters Patent.

Patented Oct. 27, 1914.

Application filed December 27, 1913. Serial No. 809,071.

To all whom it may concern:

Be it known that I, EGBERT S. CADY, a citizen of the United States, residing at Cedarville, in the county of Mackinac and State 5 of Michigan, have invented new and useful Improvements in Implements Designed for Marking Circles, of which the following is a specification.

The invention relates to an implement 10 primarily designed for marking circles of desired diameter upon plain surfaces, such as black board or the like, where it is ordinarily impossible to use the ordinary type of compass with certainty as to the result.

15 The main object of the present invention is the provision of a black board compass including means for temporarily securing the center to the black board without marking the same, and means whereby any desired radius may be readily obtained and maintained during operation.

20 The invention in its preferred form of details will be described in the following specification, reference being had particularly 25 to the accompanying drawings, in which:—

Figure 1 is a perspective view illustrating the application of the improvement. Fig. 2 is a detail perspective of the crayon clamp. Fig. 3 is a detail sectional view through the 30 handle and section cap.

In the accompanying drawings, the improved compass comprises a handle 1 at one end of which is provided a section cup 2 of any desired type, whereby the handle may 35 be fixed more or less securely to the surface on which the drawing is to be made. Immediately above the suction cup 2 the handle 1 is formed with an annular channel 3 in which is loosely seated a collar 4 having terminals 40 projecting laterally in the form of spaced ears 5. Between the ears is pivoted a compass beam 6, having appropriate scale marks 7 thereon, which may be graduated to any desired extent and are preferably arranged 45 on both sides and continued on the upper and lower edges of the said beam.

7 represents a clamp formed of a single strip of material having four arms 8, 9, 10

and 11. The arms 8 and 9 are bent to form a cylindrical casing 12 into which the crayon 50 13 is held by the resiliency of the material, the arms beyond the casing being bent on divergent lines as at 14 to provide for the convenient insertion of the crayon and to provide a handle for the operation of the device after the crayon has been inserted. The opposing arms 10 and 11 are bent in the opposite direction and formed to provide a clamp 15 to receive the scale beam, the arms beyond the clamp being formed to be connected by any suitable form of locking means to prevent disconnection from the beam. I have shown such locking means to include a lever 10' pivotally mounted in one of the arms 10 and having a right angle 60 65 portion to engage over the other arm to lock said arms together.

With the parts arranged as described, it is obvious that the handle may be attached to the black board or any other plain surface 70 and serve as a center about which the crayon may be rotated to form the circle, the clamp being freely adjustable longitudinally of the beam to arrange the crayon for the desired radius.

75 What is claimed is:—

A compass crayon clamp constructed of a single piece of material, comprising four arms projected in oppositely disposed pairs, one pair of arms being bent to form a crayon 80 receiving casing and projected beyond the casing on divergent lines, the remaining arms being projected in the opposite direction to form a member for engaging an element of the compass, said arms being projected beyond the said member, and means 85 for fastening the arms in position to cause the member to frictionally engage the element.

In testimony whereof I affix my signature 90 in presence of two witnesses.

EGBERT S. CADY.
